MECHANISM FOR FORMING COVERS ON
THE TRAYS OF TELESCOPIC BOXES

Wilmer C. Nicodemus and Hugo D. Brown, Barberton, Ohio, assignors to The Diamond Match Company, New York, N. Y., a corporation of Delaware

Application December 21, 1940, Serial No. 371,083

12 Claims. (Cl. 93—3)

This invention relates to mechanism for producing covers for and in nesting relation with the rectangular trays of slide or telescopic boxes, having reference more particularly to mechanism for forming covers about box trays supplied with matches.

The present invention may be described as an attachment for match packing machines of the kind wherein commercial box trays are supported in succeeding order by an intermittently movable conveyer, which trays as they progress are successively supplied with matches, as disclosed, for example, in Letters Patent of the United States No. 1,016,436 dated February 6, 1912. Heretofore in machines of the kind referred to each succeeding filled tray has been ejected from one side of the conveyer and nested in a pre-formed cover situated adjacent the path of the conveyer, but in the presence of an overfilled tray or of an irregularly formed cover the complementary box elements, or either of them, were subject to damage in the nesting operation.

The principal object of the invention is to overcome the objection mentioned by the provision of novel and efficient mechanism whereby a cover blank is arranged in co-operative relation to each succeeding filled tray ejected from the conveyer, and whereby the blank is formed directly about the tray, as a mandrel, in such manner as to produce a slidable cover or sheath which conforms to and encompasses the tray and its contents.

The embodiment of our invention herein illustrated comprises means whereby preformed, sanded and scored box cover blanks are successively withdrawn from a stack thereof contained in a hopper, each blank being at once imposed flatwise upon a reciprocating feeder structure and pushed therewith along to the bite of feed rolls with which a co-axial adhesive applying roll is associated. The latter roll is arranged to apply glue (or other adhesive) to the under-surface of one of the end margins of each advancing blank. Immediately the glue coating is completed the blank, leaving the feed rolls, is positioned in the path of the acting end of the feeder so that in its next effective stroke the feeder abuts the opposing edge of the blank and positively advances it to a suitable support. This support underlies a stationary former element having a rectangular throat, the area of which slightly exceeds that of the open top of the underlying tray. The former element constitutes a portion of the floor of a chamber which is arranged above and parallel with the frame struc-

ture and which chamber has a resilient lid throughout its length. As each blank is deposited on the support a filled tray is transferred from the tray conveyer of a match packing machine to and upon the top of a vertically reciprocative two-part plunger whereof the parts have capacity for independent relative vertical movement, and are effective to push the tray and the overlying opposing cover blank through the throat of the former element. Thus the body of the blank is forced slidably against the opposing walls of the throat in a manner to span the open top and at the same time bend down the projecting portions against the side walls of the filled trays. The relation of the tray to the cover blank is such that the portion of the latter having the glue-coated marginal portion depends well below the bottom of the tray thus affording side and bottom fold sections, while the other depending portion of the blank, being relatively short, affords a side fold section terminating in a narrow flap or bottom fold section. When the filled tray, thus embraced by the cover blank, has been raised by the plunger to the level of the upper surface of the former element movable supporting members are brought under the respective ends of the tray, and the plunger section adjacent the short depending portion of the blank is then slightly lowered while the other section remains up. Thereupon by means of a reciprocative folding blade the narrow terminal flap of such short portion is bent inwardly and against the bottom of the tray. This done, the tray and its cover blank, long fold leading, are bodily moved laterally and across the top of the former element. In this movement the end supports are withdrawn from the tray and the sectional plunger is lowered, and as the package progresses the leading depending portion of the cover blank, by its contact with the opposing upper surface of the former element, is drawn hard against the adjacent side and the bottom of the tray until the glued margin of the bottom fold laps the previously folded short terminal flap at the opposite side of the bottom of the tray. Hence is provided an efficient tubular sheath or cover for the complementary tray and its contents. Each filled and closed telescopic box as it progresses across the former element pushes the preceding box or boxes through the elongated chamber, the resilient lid of which maintains the underlying covers under prolonged pressure until the glued portions of the covers have become set preparatory to the discharge of the closed trays from the delivery end of the chamber. In

addition, the mechanism includes co-operatively arranged feeler and clutch devices which are effective not only to arrest the operation of the cover-blank feeding instrumentalities should an empty tray holder of the packer conveyer be inadvertently presented to the tray transfer station, but also to restart the feeder devices in timed relation to the succeeding movement of the conveyer.

The invention also comprises novel features of construction and combinations of parts, which, in a preferred form, will be hereinafter described and the scope of the invention then expressed in the appended claims.

In the drawings—

Figure 1 is a plan of a portion of a typical match packing machine equipped with mechanism embodying our invention for forming covers about the filled match trays, which trays are shown in the conveyer of the packing machine.

Fig. 2 is a front elevation of the mechanism shown in Fig. 1, the cover blanks being indicated in the magazine.

Fig. 3 is a transverse vertical section through the packing machine, as on the line 3—3 of Fig. 2, showing the cover mechanism in side elevation.

Fig. 3a is a vertical section through the reciprocating tray ejecting arm of the packing machine, as on the line 3a—3a of Fig. 3, showing the cam and adjuncts for periodically raising and lowering the arm.

Fig. 4 is a longitudinal section through the cover mechanism, as on the line 4—4 of Fig. 3, the adjacent portion of the packer being shown.

Fig. 5 is a horizontal section in a plane above the cover feed table, as on the line 5—5 of Fig. 4.

Fig. 6 is a longitudinal vertical section through the upper portion of the cover mechanism, as on the line 6—6 of Fig. 5, showing the blank feeder frame at the end of its active stroke and also a blank positioned over a filled tray which has been ejected from the packer.

Fig. 7 is a transverse section through the feed table extension and the longitudinally extending feeder bars therein, as on the line 7—7 of Fig. 6.

Fig. 8 is a view generally similar to Fig. 6, but showing the feeder frame in its retracted position.

Fig. 9 is a transverse vertical section through the cover mechanism in a plane between the feed rolls and the cover blank folding station, as on the line 9—9 of Fig. 4.

Fig. 10 is a similar section, as on the line 10—10 of Fig. 4, through the cover-blank magazine and underlying parts, showing a suction device in its down position and a blank thereby imposed on the feeder frame, the device being indicated in dotted lines in its raised position beneath the lowermost blank in the magazine.

Fig. 11 is a perspective view of the feeder frame and adjuncts, showing the frame in its retracted position, and indicating a blank in succeeding positions during its passage from beneath the magazine to the cover folding station.

Fig. 12 is a similar view of a pair of spaced guides for the cover blank in its travel, a blank being shown in position.

Fig. 13 is a partial vertical section of the cover mechanism in a plane through and longitudinally of the elongated presser and shaping chamber for the filled and closed boxes, as on the line 13—13 of Fig. 1.

Fig. 14 is a transverse vertical section through 75

the former end of the chamber, and adjuncts, showing the filled tray and the associated cover blank in raised position within the chamber, the blank thus being partially folded about the tray.

Fig. 15 is a perspective view of devices for temporarily supporting the raised tray and its contents.

Fig. 16 is a transverse vertical section through the former element and the adjacent portion 10 of the presser chamber, showing the sectional tray supporting plunger during its upward stroke within the former element, and also the relative positions of the associated tray and cover blank.

Fig. 17 is a similar view showing the plunger 15 at the limit of its upward stroke and one of its sections depressed, the tray being positioned above the former element, the movable folding blade being shown as projecting under the corner of the tray adjacent the depressed section, and the narrow end panel of the blank being thereby folded under and against the bottom of the tray.

Figs. 18 and 19 represent cams for operating the respective sections of the plunger.

Fig. 20 is a sectional perspective view of the 25 top of the plunger, one of the sections being depressed.

Fig. 21 is a perspective view showing the said sections with their tops in the same horizontal plane.

Fig. 22 is a perspective view of a horizontally reciprocative pusher head and connections for advancing the associated tray and cover along the presser chamber.

Fig. 23 is a similar view of a portion of a hinged resilient top element for the said chamber.

Figs. 24 and 25 represent in their idle and active positions, respectively, co-operatively arranged feeler and clutch devices for arresting the operation of the cover-blank feed in the absence of a tray in a holder before the holder reaches the tray ejecting station of the packer.

Fig. 26 is a vertical section through the clutch and the operating shaft of the cover mechanism, as on the line 26—26 of Fig. 25.

Fig. 27 is a perspective view of a locking and releasing clutch dog.

Fig. 28 is a general perspective view of the power transmitting means between the drive shaft of the packing machine and the operating shaft of the cover mechanism.

Fig. 29 is a partial transverse vertical section through the presser chamber, as on the line 29—29 of Fig. 13.

Fig. 30 is a perspective view of one of the walls 55 of the tray receiving trough adjacent the conveyer of the packing machine.

Fig. 31 represents a tray and cover blank in their relative positions in the succeeding steps of forming the cover about the match tray as a mandrel.

Referring to the drawings, 31 designates a portion of the intermittently-movable tray conveyer of a match packing machine, which conveyer in the form illustrated includes an endless chain of hingedly connected plates 32 carrying a succession of equally spaced holders 33 for the match trays T. The plates 32, which are mounted to slide in suitable longitudinally extending guideways 34 in the elongated supporting table 35 of the packing machine, are intermittently impelled in co-operative relation to the tray-inserting, match-supplying, and protection strip-applying stations of the machine. Thence the filled trays are carried to a station where each succeeding tray is discharged endwise from its

holder and nested in a complementary cover or "shuck" which is held in position to receive the tray. The tray ejecting devices include an ejecting head 360 on the free end of a reciprocating, rising and falling arm 36, which head has a projecting presser blade 37 which overhangs and presses down the contents of the adjacent tray. The arm 36 is pivotally mounted on a lever fast on a rock-shaft 38 under the control of a cam 39 on a shaft 40 which is geared with and driven by the main drive shaft 61 (Fig. 23) of the packing machine. The mechanism just described, excepting certain parts hereinafter pointed out, is set forth in the aforementioned Patent No. 1,016,436.

Cover forming and applying mechanism embodying our invention includes a horizontal bed structure 42 which is bolted to and extends outwardly from that side of the packer table 35 in the region of the discharging station, and which bed is also supported by a suitably disposed post 43 rising from the base 44 of the packer. Supported above and parallel with the outer end portion of the bed 42 by means of lateral bearing frames 45 on the bed, is a table 46 having a forwardly extending plate 47 slightly below its upper surface. Fixed on the table are spaced bars 48 which sustain an upstanding magazine 49 constructed and arranged to support in spaced relation to the table a stack of rectangular cover blanks C of pasteboard or other suitable material. Each blank is of proper dimensions for a match tray cover and is preferably scored and sanded, that is to say, the blank is scored transversely, as at a, to define a bottom panel b, a top panel c, two side panels d and e, and a narrow panel f at the outer edge of the side panel d, the other side panel having on its outer surface a longitudinal stripe g of friction material, such as sand. (See Fig. 12).

The magazine in the form illustrated comprises a structure within which the lateral edges of the lowermost blanks of the pile are supported by means of inwardly extending base toes 50 on lower transverse members 51 at the respective sides of the magazine. Each succeeding lowermost blank is forcibly pulled downwardly from the supporting toes 50 and imposed flatwise on a primary feeder including a frame 52 which is slidably mounted for movement toward and from the packing machine, as will presently appear.

The means for transferring the blank from the magazine to the feeder frame comprises vertically reciprocative tubes 53 which are provided at their upper ends with nipple suction cups 54, and which tubes are slidably mounted in guides 55 bolted on the bed structure 42. The lower ends of the tubes 53 are attached to flexible tubes 56 in operative communication with a suitable air exhausting element (not shown), which tubes are provided intermediate their ends with ports 530 which escape the guides 55 when the tubes are in their lowermost position, thus opening the ports and breaking the vacuum in the tubes. Clamped to the tubes 53 is a two-part fitting 57 which is connected by a depending link 58 with a rock-lever 59 fulcrumed on a bracket 60 rising from the base 44. The rock-lever 59 has a lateral roll 61 in operative contact with a cam 62 fast on a transversely extending shaft 63 having its bearings in stands 64 on the base. The shaft 63 is driven by the shaft 40 of the packing machine through bevel gearing 65, and the contour of the cam is such as to effect the periodic oscillation of the rock-lever 59 in a manner to actuate the

tubes 53 and their attached suction cups in timed relation to the feeder frame. (See Figs. 3, 4 and 28.)

The feeder frame preferably comprises a reciprocating cross-head consisting of two spaced side blocks 66 and a connecting cross-bar 67 therefor, the blocks being slidably mounted on longitudinally extending brackets 68 bolted on the outer ends of the bearing frames 45. Fastened to the cross-bar 67 are two longitudinally extending parallel bars 69, of relatively thin metal, which are slidably fitted in guideways, including gibs 70 in the top of the table 46, so as to be reciprocative upon the table extension 47 toward and from the packer. Fixed on the respective bars 69, intermediate the ends thereof, are longitudinally arranged wedge-shaped blocks 71 whereof the higher ends, when the feeder frame is moved forwardly, that is, toward the packer, provide shoulders 72 adapted to impinge the opposing end of the cover blank previously placed on the upper portions of the feeder bars by the suction devices, thus pushing the blank flatwise beyond the table 46 and entering the leading end of the blank in the bite of two corresponding pairs of suitably-located feed rolls 73 included in a secondary feeder hereinafter described. The distance between the shoulders 72 and the leading ends of the feeder bars is somewhat greater than the width of a cover blank so that when such bars are in retracted position their free ends are below the bites of the respective pairs of feed rolls.

The ends of the cross-bar 67 are pivotally connected by rods 74 with crank disks 75 on the respective ends of a transverse shaft 76 having its bearings in stands 77 formed at the respective sides of the bed structure 42. Fast on one end of the shaft 76 is a sprocket wheel 78 which is connected by means of a chain 79 with and driven from a lower similar wheel 80 having a clutch connection (hereinafter described) with the operating shaft 63 for the cover mechanism. Hence when the wheel 80 is clutched to its shaft 63, motion is transmitted to the upper shaft 76 and the crank disks 75, thus effecting the reciprocation of the feeder frame through the connecting rods 74 in timed relation with the suction devices. (See Figs. 1, 2, 3, 11 and 28.)

Shafts 81 and 82 for the upper rolls 73 of the respective pairs of feed rolls are arranged adjacent and parallel with the operating shaft 63 so that the rolls grip the leading end of the cover blank when it is initially impelled by the feeder frame. The lower shaft 82 is journaled in bearing blocks located in the side frames 77 and below the forward end of the table 46 while the upper shaft 81 is journaled in blocks slidably mounted in the frames 77 and above the table. The shafts 81 and 82 are provided at one end with meshing gears 83, the lower shaft at its opposite end having a gear 84 in mesh with a gear 85 on the crank disk shaft 76. The ratio of the gearing just described is such that the feed rolls are driven in timed relation with the feeder frame. (See Figs. 1, 4, 5, 9 and 11.)

Fast on the lower feed roll shaft 82 adjacent one end thereof is a glue applying roll 86 the periphery of which rotates in contact with the under marginal surface of the bottom panel b of the cover blank progressing between the feed rolls. The periphery of the roll 86 turns in the contents of an underlying glue pot 87, thus applying a stripe, h, of glue to the opposing under-surface of the travelling cover blank. In the

present instance the glue pot which we have adopted includes a depending reservoir 870 containing an ample supply of glue for an extended run, which reservoir has therein a screw regulated piston 871 by the manipulation of which the level of the glue in the pot can be maintained, as occasion may require.

Fast on the table extension 47 are lateral parallel guide bars 88 and 89 which are constructed and arranged to receive the adjacent edges of the blank being impelled by the feed rolls 73 and the feeder frame 52, thus uniformly guiding the sheet in its travel toward the packer.

The guide bar 88, which rearwardly terminates at the end of the table 46 beneath the bite of the feed rolls, has on its inner side a longitudinal flange 90 that overhangs and lies slightly above the table extension, thus forming a guideway for one edge of the blank, the undersurface of the flange 90 being bevelled at its receiving end, as at 920, Fig. 12. The other guide bar 89 is formed with a marginal portion 91 of inverted U-form in cross-section which not only overhangs the floor but also forms therewith a longitudinal channel guide for the adjacent edge of the cover blank. The portion 91 extends slightly above the level of the table and is downwardly bevelled at that end 92 adjacent the bite of the feed rolls. As the leading edge of the blank escapes the rolls such edge impinges the opposing bevelled surfaces 92 and 920 and is thereby deflected toward the table extension 47. Thence the two edges of the blank, in its advancement by the feed rolls, enter the respective guideways and travel therewith in proximity to the table extension 47. The portion of the table extension under the channeled portion of the guide bar 89 is longitudinally slotted, as at 93, to preclude pressure of the glued undersurface of the blank against the adjacent surface of the table extension. (See Figs. 5 to 9, inclusive, and Fig. 12.)

Overhanging the gibs 70 of the guideways of the respective feeder bars 69 and extending beneath the upper feed roll shaft 81 are a pair of horizontally movable kicker dogs 94, whereof the forward or acting ends, being undercut, as at 95, overlie and abut the trailing edge of a cover blank C presented thereto, as will presently appear. These dogs are pivoted at their rear ends to the lower portion of a pair of spaced arms 96 fixed to and depending from a rock-shaft 97 having its bearings in brackets 98 on the adjacent wall of the magazine. Also fixed to and depending from the rock-shaft 97, at one end thereof, is a crank 99 which is connected by means of a link 100 to the upper arm of a vertical lever 101 that is fulcrumed to a bracket 102 rising from the adjacent side of the table 46. On the lower arm of the lever is a lateral roll 103 which is held in operative contact with an adjacent cam 104 by means of a suitable spring 105 that is secured to the lower lever arm and a fixture 106 on the table, which cam is fast on the crank disk shaft 76. The contour of the cam 104 is such that in a determined interval of rotation of the shaft 76 the lever 101 is oscillated and the rock shaft 97 thereby actuated, thus through the arms 96 imparting forward and back motion to the two dogs.

The co-operative relation of the parts just described is such that when the blank feeding frame 52 of the primary feeder is at the limit of its rear or outer stroke the feeder bars 69 are in position to receive a cover blank from the magazine, at which stage the forward or free 70

ends of the bars 69 are in a plane directly beneath the bite of the feed rolls of the secondary feeder, or substantially so. A cover blank is then withdrawn from the magazine by the action of the suction devices previously described, and is thereby deposited on the bars 69, forwardly of the abutments 71 as seen in Fig. 8. In the initial forward stroke of the feeder frame these abutments by their contact with the opposing longitudinal edge of the blank, push the blank bodily and evenly forward so as to position its leading edge at the opposing downwardly inclined portions 92 and 920 of the respective side guides 88 and 89. Coincidentally the blank is gripped by the feed rolls 73 and is thereby advanced in and between the two side guides; it being noted that the speed of the rolls relative to the feeder frame is such that when the latter is at the limit of its forward stroke the blank is clear of the rolls and is supported throughout its length upon the feed bars, and that the rearward edge of the blank is in close relation to the shouldered ends of the overhanging dogs 94. Therefore in the next succeeding rearward stroke of the feeder frame retrograde movement of the blank is prevented. In this rearward stroke of the feeder frame the bars 69 progressively recede from the blank previously positioned in and between the guides, thus permitting the unsupported portion 20 of the blank to sink upon the table extension 47, as seen in Fig. 8. When the feeder frame completes its rearward stroke the forward ends of the bars 69 project slightly beyond the bite of the feed rolls 73 and under the rearward edge portion 25 of the preceding blank, which edge is thus in engaging relation to the dogs. The dogs then being sharply swung forward, push the opposing blank a short distance within the side guides and beyond the acting ends of the feed bars 69. 30 Thereupon the freed trailing end of the blank snaps down and in front of the adjacent ends of the feed bars. Coincidentally, another blank is withdrawn from the magazine and deposited on the feed bars and in the forward path of the abutments 71, whereupon in the next succeeding forward stroke of the feed bars the new blank is fed forward as just described in respect to the preceding blank, and the forward ends of the feed bars push the preceding blank along the guideways and project it horizontally therefrom, which ends are preferably under-cut, as at 107, to ensure their efficient engagement with the blank. Likewise in each succeeding reciprocation of the feeder frame a cover blank is withdrawn from the magazine and carried forward by the feeder frame and the feed rolls, which frame during its advancement of one blank ejects the preceding blank flatwise upon a suitably disposed support. This support, in the present instance, is afforded by the upper edge of one of the side walls 108 of an underlying bottomless trough hereinafter described, which edge underlies the side panel d of the blank. The support also includes two spaced parallel angle strips 109 so arranged that their upper inwardly extending horizontal members overhang the ends of the blank at the respective panels b and f, as and when the blank is positioned on the upper supporting edge of the wall 108. This edge, which is preferably co-extensive in length with the strips 109, projects slightly above the normal level of the advancing cover blank, the forward or receiving end of the raised edge being bevelled or rounded, as at x, Figs. 5 and 30, so as to facilitate the passage thereon of the advancing blank while the ends

of the blank pass under and are uniformly guided by the upper members of the angle strips. Hence when the flexible cover blank reaches its extreme forward position overlying the trough the blank is slightly bowed between the guide strips and thereby held in place. The depending members of the angle strips 109 prevent end displacement of the cover blank and also allow slight downward flexure of the ends of the cover in the initial upward movement of blank by the pressure thereagainst of a tray contained in the trough, as will presently appear. Moreover, since the glue is on the under marginal surface of the cover blank, the adhesive is not brought in contact with the adjacent guide rail.

One end of each of the guide strips 109 is secured to the rearward one of two spaced walls 110 rising from the bed structure and included in a housing which extends from the vicinity of the packer to the outer end of the bed, which rearward wall has therein a suitable opening 111 for the free passage of each succeeding cover blank to its position over the trough. (See Figs. 4, 5, 6, 8, 16 and 17.) The top panel *c* of the blank thus imposed on the tray support bridges the bottomless trough previously mentioned, which trough is adapted to receive each succeeding filled tray as it is endwise ejected from the packer conveyer. As shown the trough is constituted by the wall 108 and a spaced parallel side wall 112, which walls rise from a bottom end member 113 adjacent the path of the conveyer and are spaced to receive the tray between them and directly under the top panel *c* of the cover blank. The front wall 110 of the housing has therein an opening 114 through which the receiving end of the trough extends. The trough wall 112 terminates short of the top of the tray contained in the trough, and is provided with spaced upstanding members 115 having their upper ends pointed and rearwardly deflected, as at 116, so as to oppose the depending glue coated surface of the cover blank during the folding thereof about the tray as a mandrel, as will now be explained.

Mounted for vertical reciprocation into and through the open trough is a longitudinally divided plunger whereof the parts 117 and 118 have capacity for concurrent and relative vertical movement, and to that end they are slidably mounted in a vertical casing 119 which extends through an opening in the bed structure 42, and has a forwardly projecting flange 120 that is bolted to the under side of the table 35 of the packing machine. The sections of the plungers have secured thereto depending bars 120, 121, respectively, which are equipped at their lower ends with lateral rolls 122 operatively fitted in the races 123 of a pair of spaced face cams 124 and 125, respectively, fast on the operating shaft 63. The cam races are of such contour and are so disposed in relation to each other as to effect sequential movements of the two plunger sections, as follows:

Assuming a filled tray is positioned beneath a cover blank on the support 108 and the two plunger sections 117 and 118 are in down position with their tops in the same level to constitute an efficient support for the tray within the trough, the two cams in a part of their concurrent rotation simultaneously elevate the two sections, whereupon in the continued rotation of the cams there is a brief dwell of the plunger sections, during which the section 117 is slightly lowered relatively to its companion while the latter remains at rest. Then as the cams continue

and complete their rotation the two plunger sections are lowered to their previous down position, and at the same time they are relatively shifted to set their tops in the same level.

In the initial upward stroke of the plunger sections their flush heads raise the opposing tray and thrust it and the complementary tray and cover blank through the rectangular throat 126 of an upper former element comprising two spaced cheek bars 127 which are supported by and between the housing walls 110 previously referred to. The area of the throat 126 is slightly greater than that of the open top of the tray, and therefore as the associated tray and blank enter and progress upwardly through the throat the laterally projecting portions of the cover blank are forced downwardly and against the sides of the filled tray by the opposing rounded faces of the cheek bars, the upper panel (*c*) of the blank spanning the top, and the respective end portions of the blank depending below the tray and the throat of the former element; that is to say, the narrow flap panel (*a*) extends below the lower edge of the adjacent side of the tray, and the bottom panel (*b*) with the marginal stripe of glue on its inner surface extends farther below the lower edge of the other side of the tray, the glue coated surface *h* bearing against and being outwardly deflected by its contact with the opposing bearing points 116 on the adjacent wall 112 of the tray trough so as to be clear of the sectional plunger during the downward stroke of the latter. (See Figs. 16 and 17.) When the plunger is at the limit of its upward stroke the bottom of the tray is slightly above the top of the former element; thereupon when the plunger section 117 is independently lowered a short distance there is provided under the adjacent bottom portion of the tray a space 128 which permits the under bending of the narrow panel *f* of the blank against the bottom, while the tray is supported by the plunger section 118, as seen in Fig. 17. The bending or folding means herein shown comprises a blade 129 which is reciprocable in a suitable guide-way 130 in the upper surface of the adjacent cheek bar of the throat element, and is carried by a cross-head 131 slidably mounted in longitudinal guide bars 132 on the inner sides of the housing walls 110. The cross-head 131 is pivotally connected by a link 133 to the upstanding end of a lever arm 134 rising from a hub 135 loose on a stud shaft 136 projecting from a suitably disposed bracket 137 that depends from the bed structure 42. The lower lever arm 138 depends from the hub and has at its lower end a roll 139 operatively fitted in the peripheral race 140 of a cam 141 fast on the operating shaft 63. The contour of the cam race 140 is such that when the tray and its complementary cover blank are raised by the plunger and the plunger section 117 is lowered, the cross-head is moved toward the tray, thus forcing the blade against the opposing narrow panel *f* and thereby bending it under and against the bottom of the tray, so maintaining the blade for a brief interval preparatory to its retraction.

In order to provide a relatively broad supporting surface for the tray when the elevated plunger section 117 is initially lowered preparatory to the active stroke of the blade 129, the companion section 118 is provided with a top plate 142 having an extended inner portion 143 which overhangs the section 117, and the latter section is provided with a narrow top plate 144 which is coplanar with the plate 142 when the two plunger

sections are in joint tray supporting relation. (See Figs. 13, 16, 17, 20 and 21.)

The top plate 142 has formed therein, at its end corners remote from the extended portion 143, recesses 145 which permit the free passage of horizontally swinging toes 146 (Figs. 14 and 15) under the adjacent corners of the tray while the folder blade 129 is under the bottom of the tray, which toes and blade thus effectually support the partially covered tray at the top of the throat of the former element when the plunger sections are subsequently lowered. The housing walls 110 have therein suitably disposed openings 147 for the free passage of the toes, each of which toes is constituted by one arm of a horizontal angle member whereof the other arm 241 is fixed to the lower end of a vertical pivot pin 148 having its bearing in a bracket 149 on the outer side of the adjacent housing wall 110. Fast on the upper end of the pivot pin is an actuating arm 150 which is parallel, or substantially so, with the angle arm 241, and has at its end a roll 151 that extends into a reciprocating casing 152 having a lateral cam wall 153 which, by the reciprocation of the casing, bears against and recedes from the roll 151, thus swinging the arm 150 and positioning the toe under and from the adjacent bottom end corner of the tray.

The cam casings 152 for the respective toes 146 are mounted on parallel horizontal bars 154 slidably fitted in suitably disposed exterior brackets 155 on the respective housing walls 110. The ends of the bars 154 remote from the former element extend beyond the bed structure 42 and are pivotally connected to levers arms 156 rising from a rock-shaft 157 having its bearings in a bracket 158 extending from the bottom of the structure. Depending from the shaft 157 is an arm 258 having at its lower end a roll 159 which is operatively fitted in the peripheral race 160 of a cam 161 on the operating shaft 63. (See Fig. 2.) The contour of the cam race is such as to effect the periodic actuation of the lever arms 156, thus reciprocating the cam bars 154 to swing the toes 146 under and retract them from the respective ends of the bottom of the tray, as previously mentioned. (See Figs. 1, 2, 3, 13, 14 and 15.)

Upon the descent of the plunger sections 117 and 118 when the partially-covered tray is supported on the folder blade 129 and the inwardly extending toes 146, such tray is bodily pushed from its supports and across the former element by means of a reciprocative cross-head 162 which in its effective stroke presses evenly against the opposing covered side of the tray adjacent the packer. As the partially covered tray is initially advanced by the cross-head the leading depending portion of the blank by its contact with the side and the top of the opposing cheek bar of the former element, is folded upward and against the bottom of the tray, the glue-coated marginal portion of the blank lapping and adhering to the previously folded narrow panel *f* of the blank. (See Fig. 13.)

The reduced ends 163 of the cross head 162 extend outwardly through longitudinal guide slots 164 in the respective housing walls 110 and are secured to parallel side bars 165 that are slidably fitted in longitudinally extending guideways 166 (Figs. 4 and 14) in the outer surfaces of the housing walls. The rearward ends of the bars 165 are pivotally connected to arms 167 rising from a rock-shaft 168 having its bearings in a bracket 169 depending from the bed structure 42, which rock-shaft is in spaced parallel relation

to the rock shaft 157 previously referred to. The shaft 168, similarly to the shaft 157, is provided with a depending actuating arm 170 having at its lower end a roll 171 which is operatively fitted in the peripheral race 172 of a cam 173 on the operating shaft 63. The contour of the cam race 172 is such as to effect through the lever connections the periodic reciprocation of the slide bars 165, thus reciprocating the cross head 162 in relation to the tray and cover supported over the throat of the former element constituted by the cheek bars 127. (See Figs. 2, 13 and 22.)

The top of the former element is in the same level as and constitutes, in effect, a continuation of a floor 174 which is suitably arranged between and longitudinally of the upper portions of the side walls 110 of the housing so as to provide an elongated chamber of a width and height corresponding respectively with the length and height of a tray, or substantially so. Hence in each reciprocation of the cross-head 162 a tray with its complementary cover is pushed from the former element, and at the same time each succeeding tray advances the preceding covered trays along the chamber. The floor 174 is preferably provided with a top plate 175 having its upper surface concave in cross-section so as to present small supporting surfaces to the lower end corners of each of the covered trays as it advances in the chamber. (See Fig. 29.) This chamber, which constitutes a glue-drying and shaping passage for the covers of the progressing trays, is equipped throughout its length with a suitable lid. The lid illustrated comprises a frame including two parallel side rails 176 adapted to rest upon the respective side walls of the housing, and also to support the offset ends 177 of a succession of close lying plates 178 having smooth coplanar undersurfaces that are under resilient pressure so as to bear independently and yieldingly upon the opposing covers of the confined closed trays. For this purpose the ends of each plate 178 are provided with openings 179 for the free passage of upstanding guide pins 180 rising from the respective rails 176, and compression springs 181, which encircle the pins, are interposed between the opposing rails and suitably-disposed nuts or stops 182 on the pins. Preferably the ends of the rails 176 in the vicinity of the former element are hingedly connected to a stationary cross-bar 183 which is fixed to the housing walls 110, and the opposite ends of the rails are connected by a cross-bar 184 which, when the lid is in closing position, is detachably secured to the respective walls 110 by means, for example, of the T-nuts 185 of upstanding bolts 186 on the housing walls adjacent the cross-bar 184. The nuts may be readily turned to release the bar 184, and the hinged lid then be bodily swung upward to facilitate access to the contents of the chamber throughout its length, as occasion may require. (See Figs. 13, 14, 16 and 17.)

It is to be noted that the resilient plate 178 at the receiving end of the elongated chamber directly overlies the throat of the former element so that when each filled tray and its cover blank are pushed up through the throat by the plunger the top portion of the partially folded blank bears against the opposing resilient plate, in consequence of which the contents of the tray are compacted in a manner to brace internally the walls of the tray and thereby provide a firm mandrel-like structure for the formation of the encasing cover.

At the outer end of the chamber just described

and constituting in effect, a continuation thereof, is supported a trough 187 of similar cross-section into which the closed match trays are delivered in succeeding order, thence progressing to a point of discharge. Loosely mounted in sockets in the side walls of the trough are the trunnions of spaced parallel rollers 188, relatively heavy, which bear upon the tops of the underlying travelling match trays, thus in conjunction with the trough contributing to the proper shaping of each cover about its filled tray.

Recurring to the match packing machine it is to be noted that in the prior patented construction provision was made for firmly holding the cover in position to receive and retain a filled tray when the latter was discharged from the tray holder of the conveyer by the ejecting head, and that the pressure blade in the effective stroke of the head passed between the tray and the top of the cover to facilitate the nesting of the box elements, thus remaining until the withdrawal of the blade in the return stroke of the head. In the present construction the filled tray when it is ejected from the holder of the conveyer is loosely positioned within the trough in accurate relation to the plunger element and the overlying cover blank. Hence the mechanism for raising and lowering the arm 36 that carries the tray-ejecting head is of such character that in the effective stroke of the arm to eject the tray and position it in the trough, the arm is held in down position with the presser blade 37 bearing upon the contents of the tray until the stroke is completed, whereupon the arm is immediately raised and held during its return stroke, thus lifting the blade from the contents of the tray and precluding displacement of the tray by the blade in its return stroke. To this end the arm is yieldingly held in contact with an underlying rotary cam 361 which is fast on a short shaft 362 journaled in brackets 363 on the packer table. Fixed on the shaft 362 is a sprocket wheel 364 which is connected by means of a chain 365 with a similar wheel 366 on the continuously driven operating shaft 63 previously described, the ratio of the gearing being such that the shaft 362 and its cam 361 are driven at the same speed as the shaft 63. The contour of the cam is such that when the arm 36 is at the end of its back stroke an arcuate concavity 367 in the lower surface of the arm rests upon the high part of the cam, being yieldingly held thereon by a suitably disposed spring member 338 that bears upon the arm. Thus the presser blade 37 is supported in spaced overhanging relation to the path of the filled tray in a holder 33 of the conveyer. In the initial forward stroke of the arm as the cam continues its clockwise rotation in contact therewith, the low part of the cam is presented to the arm 36, in consequence of which the head 360, descending, abuts the opposing tray in the conveyer while the blade is pressed down upon the contents of the tray. The head thus remains until it reaches the end of its effective stroke and has properly positioned the filled tray within the trough. At this stage the high part of the rotating cam is presented to a suitably located arcuate concavity 369 in the lower surface of the arm, thus raising the arm and maintaining it in that position until the arm has reached the limit of its return stroke, at which time the concavity 367 of the arm and the high part of the cam are in contactual relation. (See Figs. 3 and 3a.)

Occasionally an underfilled or other faulty tray is removed from a tray holder of the packer con-

veyer after the tray leaves the match filling station of the packer and before it reaches the path of the ejecting head 363, in which event an empty tray holder 33 is located by the conveyer in the path of the tray ejecting head. To meet that condition when it arises we have provided mechanism for automatically arresting the operation of the feeder actuating shaft 76 until the empty holder (or a series of consecutive empty holders) shall pass the path of the ejecting head, whereupon the shaft is restarted and continued until another empty holder or holders are presented to the ejecting head, and so on. The stopping and starting mechanism illustrated is as follows, reference being had to Figs. 2 and 24 to 27, inclusive of the drawings:

As hereinbefore mentioned the sprocket wheel 80 from which motion is transmitted to the sprocket wheel 78 on the feeder actuating shaft 76, has a clutch connection with the continuously driven operating shaft 63. This connection includes two relatively movable clutch elements 189 and 190, whereof the element 189 comprises a cylindrical head having a socketed portion 191 with an internal longitudinally extending groove 192, which head is fast on the shaft 63, and whereof the element 190 comprises a head which is loose on the shaft 63 and has a reduced portion or hub 193 rotatably fitted in the socketed portion 191, as seen in Fig. 26. The outer end of the head 190 has also a peripheral flange 194 to which the sprocket wheel 80 included in the gearing between the shafts 63 and 76 is bolted or otherwise secured. The hub 193 has a longitudinally-extending peripheral channel 195 of semi-circular cross-section, which by relative movement of the two clutch elements may be brought into registry with the groove of the element 189. Rockably mounted in the outer end of the element 190 is a clutch dog comprising a cylindrical pin 196, having a reduced portion 197 which is seated in the channel of the element 190. This portion 197 is semi-circular in cross-section, its outer surface being rounded correspondingly with the periphery of the head, as at 198, so that when the pin is seated within the channel 195 with the surface 198 coincident with the periphery of the hub 193, the clutch element 189 is free to turn about the complementary element 190, and the sprocket wheel 80 is therefore idle. But when the groove 192 and channel 195 are in registry and the pin 196 is slightly turned about its axis one corner of the pin projects into the groove 192 of the rotating clutch element 189 and abuts the opposing shoulder presented by a side wall of the groove 192, thereby bodily rotating the clutch element 190 and its sprocket wheel 80 concurrently with the shaft 63. The dog also includes a trip trigger 199 which is fixed to the outer end of the pin 196, adjacent the flange 194, and is movable to and fro within a cutout 200 of the flange. A spring 201 suitably supported on the flange bears against the trigger 199 of the dog and tends normally to maintain the pin in locking relation to the groove 192 of the element 189, as seen in Fig. 24.

Fast on the shaft 63, laterally of the flange 194, is a cam 202 upon the periphery of which rests a roll 203 on the free end of a vertically movable latch arm 204, which end has a depending tooth 208. The opposite end of the latch arm is loosely mounted on an eccentric 305 fast on or forming a part of a shaft 206 having its bearings in spaced standards 206 on the base of the packer. The shaft 205 has fast

thereon a sprocket wheel 306 which is connected by a chain 307 to a similar wheel 308 fast on the clutch element 189. Thus motion is transmitted from the operating shaft 63 to the shaft 205, in consequence of which the eccentric 305 longitudinally reciprocates the latch arm. The extent of descent of the latch arm is determined by the presence or absence of a match tray or trays in the path of a feeler connected with the pawl, as will presently appear.

The cam 202 comprises a disk having a depressed peripheral cam surface 207 which in a partial rotation of the shaft 63 while the conveyer is at rest permits the latch arm 204 to drop and thus position its tooth 208 for a determined interval in the path of the upstanding trigger 199 of the clutch dog if and when an empty tray holder 33 of the intermittently moving conveyer approaches the tray ejecting station. Thus as the clutch elements concurrently rotate the trigger by its contact with the tooth of the latch arm is swung slightly backward, thereby disengaging the pin 196 from the groove 192 of the clutch element 189 and, perforce, unclutching the feeder shaft 76 from the operating shaft 63. This done, the feeder shaft is idle until a holder containing a tray is advanced to and comes to rest in the path of the feeler, whereupon the latch arm is raised, the clutch dog resumes its normal or clutching position, and the feeder shaft is actuated.

The feeler comprises a plate 209 which overhangs each of the tray holders in its dwell next preceding its step to the path of the ejecting head 360, which plate is attached by means of an arm 210 to the upper end of a vertical plunger 211 slidably fitted in a bracket 212 on the adjacent housing wall 110, the lower end of the plunger being pivotally connected by means of a link 213 with the latch arm. The spaced relation of the plate 209 to the path of the tray conveyer 33 of the packer is such that upon the escape of the roll 203 of the latch arm from the higher peripheral surface of the cam, when a holder containing a filled tray underlies the plate, the descent of the plate is prevented by its contact with the tray or the contents of the tray, and therefore the dropping of the latch tooth in the path of the trigger 199 is prevented, it being noted that when the roll is riding on the higher surface of the cam the latch tooth is above the path of rotation of the free end of the trigger. (See Fig. 24.) If, however, the tray holder when it is positioned under the feeler, be empty, the feeler, descending within the holder, will permit the roll of the latch arm to drop within the cam depression 207 and the latch tooth then be located to oppose the rotating trigger 199 of the dog. Since in the latter case the feeder shaft 76 is idle the feeder frame 52 remains in its retracted position under the magazine, at which time the suction unit is in no way affected by the stoppage of the shaft 76, except that a cover blank instead of its being deposited on the feeder frame is simply moved up and down with the suction cups until the feeder shaft is reclutched to the operating shaft. Thereupon the feeder frame, feed rolls and adjuncts are co-operatively actuated, such feed frame in its forward stroke pushing the blank into the bite of the feed rolls and the sequence of operations being continued as previously explained until another empty holder approaches the tray ejecting station.

It is manifest that if a series of two or more match trays be absent from consecutive holders of the conveyer the latch tooth 208 in each rotation of the shaft 63 will reengage the trigger 199 of the clutch dog just before the driving groove 192 in the clutch element 189 reaches the pin of the clutch dog, the action being continued until the dog shall be caused to reengage the groove 192 by the presence of a tray in a holder situated beneath the feeler. Thus ordinarily a cover blank cannot be advanced by the feeder mechanism unless a complementary tray therefor is discharged from the conveyer of the packing machine. However, in order to obviate liability of the premature engagement of the latch tooth with the trip trigger 199 of the clutch dog, on account of the momentum or forward lash of the trigger, when two or more boxes are missing in succession, (thus resulting in the feeding of a cover blank in the absence of a tray in the bottomless trough) the eccentric mounting previously described for the latch arm 204 is provided; that is to say, the eccentric is in the extreme back position when the trip abuts the tooth of the latch arm, and as the rotation of the eccentric continues the latch arm is moved forwardly thereby while the latter is descending in the absence of a tray in the conveyer, which latch arm is then returned to its back position in proper sequence.

It is to be understood that the invention is not limited to the particular exemplifying form thereof herein disclosed, as the mechanisms may be modified within the principle of the invention and the scope of the appended claims.

We claim:

1. The combination of a vertically-reciprocatively longitudinally-divided plunger whereof the parts have capacity for concurrent and also relative vertical movement, a stationary former element having a throat above and in co-operative relation to the plunger, means for supporting a cover blank flatwise under said former element and in overhanging relation to the plunger, a horizontally reciprocative folder blade movable over and from one side of the throat, means for simultaneously elevating the two parts of the plunger so that a tray associated with a cover blank is pushed through and above the said throat by the plunger to cause the blank to span the top and embrace the sides of the tray, said latter means thereafter independently lowering a short distance the part of the plunger adjacent the path of the folder blade, thus providing a clearance space for the blade and the opposing fold of the blank, and finally lowering the two parts of the plunger to their previous position and with their tops in the same level, and means for reciprocating the folder blade in timed relation to the plunger.

2. The combination of a vertically-reciprocatively longitudinally-divided plunger whereof the parts have capacity for concurrent and also relative vertical movement, one of said parts having a head portion partially overhanging the other part of the plunger and said other part having a head portion freely movable in close relation to said overhanging portion, whereby said head portions can assume a common level at the respective limits of each stroke of the plunger, a stationary former element having a throat above and in co-operative relation to the plunger, means for supporting a cover blank flatwise under said former element and in overhanging relation to the plunger, a horizontally reciprocative folder

blade movable over and from one side of the throat, means for simultaneously elevating the two parts of the plunger to a common level substantially at the top of the throat, thus causing the blank to span the top and embrace the sides of a tray supported on the plunger parts, said latter means thereafter independently lowering a short distance the part of the plunger adjacent the path of the folder blade, thus providing a clearance space for the blade and the opposing fold of the blank, and finally lowering the two parts of the plunger to their previous position and with their tops in the same level for the support of a succeeding tray, and means for reciprocating the said blade in timed relation to the plunger.

3. The combination of a vertically reciprocating plunger to support and elevate a tray and an overhanging cover blank, a stationary former element having a throat above and in co-operative relation to the plunger, means for supporting a cover flatwise under said former element and in overhanging relation to the plunger, whereby in the upward stroke of the plunger the tray and the blank are moved through the throat element, thus folding the blank across the open top and against the two sides of the tray, a horizontally reciprocative folder blade movable over and from one side of the throat and beneath the partially covered tray, tray supporting members spaced from the folder blade and movable under and from the respective ends of the tray, and means for actuating said plunger, blade and supporting members in timed relation, whereby the blade and members underlie and support the tray during the descent of the plunger.

4. The combination of a vertically reciprocating plunger to receive and support a tray, a stationary former element having a throat above and in co-operative relation to the plunger, means for supporting flatwise under said former element and in overhanging relation to the plunger a cover blank having on its under surface a marginal coating of adhesive, whereby in the upward stroke of the plunger the tray and the blank are moved through the throat element, thus folding the blank across the open top and against the two sides of the tray, and lateral projections arranged to oppose the adhesive coated margin of the blank and deflect it beyond the adjacent side of the elevated plunger, thus maintaining said margin until the descent of the plunger.

5. The combination of a vertically reciprocating plunger to receive and support a tray, a stationary former element having a throat above and in co-operative relation to the plunger, means for supporting flatwise under said former element and in overhanging relation to the plunger a cover blank having on its under surface a marginal coating of adhesive, whereby in the upward stroke of the plunger the tray and the blank are moved through the throat element, thus folding the blank across the open top and against the two sides of the tray, and means comprising spaced bearing points located to oppose the adhesive coated margin of the blank and deflect it beyond the adjacent side of the elevated plunger, thus maintaining said margin until the descent of the plunger.

6. The combination of a vertically reciprocating plunger to receive and support a filled tray, a stationary former element having a throat above and in co-operative relation to the plunger, means for supporting flatwise under said former element and in overhanging relation to the

plunger a cover blank, whereby in the upward stroke of the plunger the tray and the blank are moved through the throat element, thus folding the blank across the open top and against the two sides of the tray, and a resilient pressure plate overlying the former element in opposition to the tray and cover blank, whereby the contents of the tray is compacted and the walls of the tray are internally braced to provide a firm mandrel-like structure.

7. The combination of a vertically reciprocating plunger to receive and support a filled tray, a stationary former element having a throat above and in co-operative relation to the plunger, means for supporting flatwise under the former element and in overlying relation to the plunger a cover blank whereby in the upper stroke of the plunger the tray and the blank are moved through the throat element, thus folding the blank across the open top and against the two sides of the tray, an elongated chamber the receiving end of the floor of which is constituted by the former element, a lid for said chamber comprising a succession of resilient pressure plates one of which overlies the former element in opposition to the tray and cover blank, means for folding one end of the blank under the outer bottom corner of the tray, and means for pushing the partially covered box across the throat element and along the chamber, whereby the other end of the blank is folded against the bottom of the tray in lapping relation to the other bottom fold, and whereby the box is maintained under pressure during its passage through the chamber.

8. The combination of a vertically reciprocating plunger to receive and support a tray, a stationary former element having a throat above and in co-operative relation to the plunger, and means for supporting under said former element and in overhanging relation to the plunger a flexible cover blank, said means comprising spaced parallel guide members and a relatively thin member therebetween having its upper edge at a slightly higher level than the guide members, whereby the body of the blank bears upon the said edge while the upper end surfaces of the blank underlie and are pressed against the guide members.

9. The combination with an intermittently movable conveyer for a succession of filled trays, and tray receiving means laterally of the path of said conveyer, of a pivotally mounted reciprocating arm having a head for transferring each succeeding tray from said conveyer to the said receiving means, said arm also having spaced cam concavities in its under surface, a presser blade projecting forwardly from said head in overhanging relation to an adjacent tray in the conveyer, a rotary supporting cam having high and low portions for respectively raising and permitting the descent of the arm and the presser blade in relation to the tray, and means for rotating said cam in timed relation to the reciprocating arm, whereby one of said concavities is seated on the low part of the cam when the arm is at the limit of its effective stroke and whereby the other concavity is seated on the high part of the cam when the arm is at the limit of its return stroke.

10. The combination with an intermittently movable conveyer for a succession of filled trays, cover applying mechanism located adjacent said conveyer and including means for supporting a tray laterally of the conveyer, means for sup-

porting cover material above said tray supporting means and means for feeding said material to the material supporting means, and means for transferring each succeeding tray from said conveyer to the said tray supporting means, of a continuously driven shaft, transmission devices between said shaft and the said feeding means, a clutch between said transmission devices and the shaft comprising two complementary elements fast and loose respectively on said shaft, a coupling for the two elements, said coupling including a projecting trigger member, a latch arm having an abutment movable into and from the path of said trigger member, a vertically reciprocating feeler overhanging the path of each succeeding tray in the region of the said transfer means, means for reciprocating said feeler in timed relation to the conveyer, and operative connection between said feeler and the latch arm.

11. The combination with an intermittently movable conveyer for a succession of filled trays, cover applying mechanism located adjacent said conveyer and including means for supporting a tray laterally of the conveyer, means for supporting cover material above said tray supporting means and means for feeding said material to the material supporting means, and means for transferring each succeeding tray from said conveyer to the said tray supporting means, of a continuously driven shaft, transmission devices between said shaft and the said feeding means, a clutch between said transmission devices and the shaft comprising two complementary elements fast and loose respectively on said shaft, a coupling for the two elements, said coupling including a projecting trigger member, a latch arm

having an abutment movable into and from the path of said trigger, a mounting for said latch arm including an eccentric for longitudinally reciprocating the arm, means for actuating said eccentric in timed relation to the shaft, a vertically reciprocating feeler overhanging the path of each succeeding tray in the region of the said transfer means, means for reciprocating said feeler in timed relation to the conveyer, and operative connection between said feeler and the latch arm.

12. The combination with an intermittently movable conveyer having a succession of holders for filled trays, means for ejecting the contained tray of each succeeding holder, cover applying mechanism located adjacent said conveyer, said mechanism comprising a vertically reciprocative element for receiving a tray as it is ejected from a holder, means for feeding a cover blank and positioning it in the effective path of said element, a former member through which the tray and the cover blank are elevated by the said element, a continuously driven shaft, and transmission devices between said driven shaft and the cover-feeding means, of a clutch between said transmission devices and the driven shaft, a vertically reciprocating feeler overhanging the path of each succeeding holder in the region of the tray ejecting means, means for reciprocating said feeler in timed relation to the conveyer, and trip devices under the control of the feeler for actuating said clutch to release the transmission devices from said driven shaft when an empty holder underlies the feeler.
